METHOD OF FORMING CURVED CHANNEL
MEMBERS, ELBOWS, AND U-BENDS

James J. Smith, Philadelphia, Pa.

Application May 2, 1941, Serial No. 391,578

4 Claims. (Cl. 29—157)

(Granted under the act of March 3, 1883, as
amended April 30, 1928; 370 O. G. 757)

This application is a continuation-in-part of application Serial No. 357,333, filed September 18, 1940, which was a refile application for an abandoned application Serial No. 106,636, filed October 20, 1936.

The object of the invention is primarily to provide an improved method of forming elbows, U-bends, and channel members, which method makes it possible to create such articles more perfectly and inexpensively in the case of channel members of any size, and from any ductile metal of any thickness for either high or low pressure elbows than heretofore, and also makes it possible to form from metal plates of any thickness articles of this nature, which heretofore have had to be made of cast metal, it being understood that the term "bend" is the term heretofore used, to describe the resulting article by the method by which it was formed, whereas a so-called "bend" by the improved method is not, accurately speaking, a bend, but like the older form of the article is a curved section, of 45 degrees, 90 degrees, 180 degrees, etc.

More particularly, the object of the present invention is to provide an improved method of making a curved section of channel member, pipe or tubing from metal plates by a different series of steps than those heretofore employed, and in which the thickness of the metal in the resulting article is the same at all points, as for instance in the radially outer and the radially inner portions of the curve, as well as at points intermediate thereof.

With the objects of the invention thus broadly stated, the detailed steps comprising the invention are hereinafter fully brought out in the following description, when read in conjunction with the accompanying drawings in which:

Figs. 1 and 2 are plan views of metal plate blanks from which half portions of 90 and 180 degree sections are to be formed;

Fig. 3 is a section on the lines 3—3 of each of Figs. 1 and 2;

Fig. 4 is a top plan view of the concavely channeled die and forming roller in operative relation;

Fig. 5 is a section on the line 5—5 of Fig. 4, showing a metal plate blank positioned between the roller and the die but before being formed thereby;

Fig. 6 is a similar sectional view after the roller and die have formed the interpositioned blank;

Fig. 7 is a plan view showing two curved sec-

tions oppositely positioned with respect to each other, but before being integrally united;

Fig. 8 is a similar view after being united to form a curved pipe section;

Fig. 9 is a plan view of an annular terminal flange;

Fig. 10 is a plan view of the curved pipe section of Fig. 8 after two of the terminal flanges have also been secured integrally thereto;

Fig. 11 is a plan view of a completed blank still in the forming die, which blank has a 90 degree curved channel portion with straight sections at its ends;

Fig. 12 is a section on line 12—12 of Fig. 11 showing the plane straight end portions of Fig. 11;

Fig. 13 is a sectional view showing the channeled curved portion on line 13—13 of Fig. 11; and

Fig. 14 is a cross sectional view of various shapes that have been formed according to this invention.

Referring to the drawings, there is illustrated in Fig. 1 an arcuate metal plate or equivalent blank 1 of 90° curvature, and in Fig. 2 a similar blank 2 of 180° curvature, the transverse shape of these blanks being indicated by Fig. 3. It is to be borne in mind that the 90° and 180° curvatures represented by Figs. 1 and 2 are merely illustrative of any curvature, which may be necessary to provide for the formation of a channel member or curved pipe section such as is usually referred to as an elbow, U-bend, or similarly, it being understood that a pair of duplicate blanks are provided for each such curved pipe section.

Referring to Figs. 4, 5, and 6, there is shown a forming die 3 of any desired cross section, except that it is definitely provided with a curved recess or trough 4, which in this figure is shown as being semi-circular in cross section and in plan is of the same curvature, whether regular or irregular, as that of the finished channel member or pipe section, it also being understood that channel members or pipe sections having the shapes similar to or suggestive of a C, J, O, S, or the like, may be formed, as well as L's and U-bends, above referred to. In any such case, a roller 5 is mounted upon a suitable shaft or other support 6, and by any suitable apparatus (not shown) is guided through a path parallel with the center line of the said trough or concave recess in the forming die. The shape and size of said roller is such that it corresponds with the transverse shape of said trough or recess, but is sufficiently smaller than the latter to provide for the rolling

and interpositioning of one of said blanks therebetween, as shown in Fig. 6, it being further understood at this point that the present method anticipates the formation of curved channel members or pipe sections having channel, elliptical, ovoid and similar cross sections, other than circular.

In carrying out the present method, a blank is first laid upon the preferably, though not necessarily, planular upper surface 1 of the forming die 3, after which said die and roller are moved relative to each other, with the roller in the upright position shown in Fig. 5, while gradually increasing pressure is applied to said roller, to thereby force said blank into the trough or recess 4, until it accurately conforms to the transverse shape of the latter, as shown in Fig. 6. If a pipe is being made, after forming a pair of such semi-tubular sections 8 and 9, they are placed in parallel relation with each other, as shown in Fig. 7, then brought together and welded along the line of their adjacent edge surfaces 10, to provide a pair of integral reinforced seams 11, as shown in Fig. 8.

As it is difficult in practice to so shape the original blank, that its edges when removed from the forming die will be absolutely smooth and lie in the same plane, it has been found advisable to grind the said edges so as to provide planular surfaces, after the semi-tubular section has been removed from said forming die. Having completed a curved pipe section, provision for connecting the ends of the same to other sections of straight or curved pipe is made by integrally securing, as by welding, an annular flange 12 upon and about either or both of the ends of the curved section, as shown in Fig. 10, said flanges, if desired, being provided with apertures or other form of cutout regions, for connecting together pairs of them upon adjacent pipe sections by any suitable fastening means, such as bolts, clamps, or the like.

In Fig. 11 the method of this invention is shown as forming a channel portion in a curved segment of a plane blank. As shown at 13 in Fig. 12, the entire blank is originally in the same plane and includes a curved center portion 14 of 90 degrees radius and having straight end portions 15 and 16. As applied to this form, the blank 13 is placed with its curved center portion 14 over the curved forming die 17 and then rolled into this die 17 by a roller of appropriate shape but otherwise identical in operation and construction with the roller 5 to provide the channel portion 14 as shown in Fig. 13. Obviously, plane end sections 15 and 16 may be omitted, in which case the channel shaped portion 14 would end at the ends of the die 17. Likewise it is contemplated that the straight sections 15 and 16 could be formed into a channel section similar to the curved channel section 14 by merely providing an appropriately shaped die and passing the roller along such straight portions of the die 17.

Although, as shown in Figs. 1 to 6, the transverse shape of the completed curve member is circular in cross section and, as shown in Fig. 13, the transverse shape is channeled shaped in the cross section, it is obvious by making the trough die member and the rolling ball of suitable complementary shapes, any desired cross section may be provided in the completed article. A variety of such cross sections successfully completed by this invention are shown generally in Fig. 14, at 20 to 38 inclusive.

Tests have proved or established the fact, that

curved channel members or pipe sections formed by this improved method are entirely free from cracks resulting from stretching, or crimps resulting from forced contraction, and are also entirely free from any portions of either thicker or thinner dimensions than that of the original blank, by contrast with tubes or channel members which are curved to provide curved channel members, elbows, U-bends, and the like, and in which case the radially center portions are thinner, due to stretching and the radially inner portions are thicker and often show crimps, due to compression about a curved surface or guide. Thus, the product of the present improved method is characterized not only by uniform thickness, but also uniform internal tensions or stresses.

It should be borne in mind that the present method involves the important and unprecedented principle which consists in rolling the metal of the blank plate two ways simultaneously, that is, vertically or at right angles with respect to the plane of the die and also angularly about the center or axis of the groove or trough within the die. It is generally considered by experts in the art that such treatment of metal is both impracticable and impossible of accomplishment.

In interpreting the appended claims, it is to be understood that the particular form of the device hereinbefore described, and illustrated in the accompanying drawings, is merely illustrative of some embodiments of the invention, and that said invention is capable of being modified in many ways, as to the exact details of its construction and operation, without departing from the scope of the appended claims.

The invention herein described and claimed may be used and manufactured by or for the Government of the United States of America for governmental purposes without the payment of any royalties thereon or therefor.

What is claimed is:

1. The method of forming a curved pipe section, which consists in providing a pair of flat plate blanks defined transversely by a pair of substantially concentric edges, the medial radius of each blank being substantially the same as that of the finished pipe section, progressively rolling said blanks along an arc having said medial radius by gradually increasing pressure into a trough-shape to cause both a transverse and a longitudinal flow of metal, thereby producing a uniform wall thickness, and then integrally uniting the corresponding edges of said sections.
- 45 2. The method of forming a curved pipe section, which consists in providing a pair of flat segmental plate blanks having medial radii the same as that of the finished section, progressively rolling said blanks into the longitudinally curved concave trough of a forming die, which is transversely equal to substantially one-half of the cross-section of the finished pipe section, to form complementary, semi-cylindrical longitudinally curved pipe sections, the radius of said trough being also the same as that of the finished pipe section, and then integrally uniting said blanks along their corresponding edges.
- 55 3. The method of forming the curved portion of a sheet metal member into a channel curved about an arc of a circle which consists in providing a flat plate metal blank having a curved portion defined transversely by a pair of substantially concentric circular edges and having a medial radius substantially the same as that of the finished channel, rolling the said blank along
- 60
- 65
- 70
- 75

a circular arc having the said medial radius to bend only the medial portion of the blank into the desired concave cross sections, continuing the rolling along the said arc with increased pressure to progressively bend the said blank on each side of the first formed portion to the desired shape, and finally rolling along said arc the progressively bent blank throughout its radial extent at the same time and throughout its extent in the direction of rolling to provide a uniform curvature.

4. The method of forming the curved portion of a sheet metal member into a channel curved about an arc of a circle which consists in providing a flat plate metal blank having a curved por-

5 tion defined transversely by a pair of substantially concentric circular edges and having a medial radius substantially the same as that of the finished channel, rolling the said blank along a circular arc having the said medial radius to bend only the medial portion of the blank into the desired cross sections, continuing the rolling along the said arc with increased pressure to progressively bend the said blank on each side of the first formed portion to the desired shape, and finally rolling along said arc the progressively bent blank throughout its radial extent at the same time and throughout its extent in the direction of rolling to provide a uniform curvature.
